UNITED STATES PATENT OFFICE

GEORGE L. MARBLE, OF ROCHESTER, NEW YORK

SWORD

Application filed May 7, 1930. Serial No. 450,567.

The present invention relates to swords and an object of the same is to provide a simple take down construction which will permit the sword to be stored in an ordinary suitcase. Another object of the invention is to provide a novel construction which will permit the handle or grip, the guard and the blade to be readily connected or disconnected.

To these and other ends, the invention consists of certain parts and combinations of parts, all of which will be hereinafter described: the novel features being pointed out in the appended claims.

In the drawing:

Fig. 1 is a side view of a sword embodying the present invention;

Fig. 2 is a fragmentary longitudinal section;

Fig. 3 shows fragments of the handle or grip and the blade in slightly separated relation to the guard;

Fig. 4 is a section on the line 4—4, Fig. 2; and

Fig. 5 is a section on the line 5—5, Fig. 2.

In the illustrated embodiment of the invention 1 indicates a tube forming the stem part of the handle and surrounded by a handle sleeve or grip portion 2 which abuts a

head 3 at its outer end and a collar 4 at its inner end. The collar is arranged in spaced relation to the inner end of the tube or stem 1 so that the latter projects at 5 beyond the collar and the latter serves as a transversely extending abutment for the guard 6 which fits on the projecting portion. In order to prevent lateral play or looseness of the guard on the projecting portion, the latter has a flaring portion 7 at its inner end and the opening in the guard is flared at 8. The length of the opening in the guard is slightly longer than the projection 5 so that the guard projects slightly beyond the end of the projection in order that the guard may be firmly clamped against the collar 4.

The projecting portion 5 is provided with internal threads preferably double threads of high pitch for engagement with a like threaded tang 9 projected from the inner end of the blade 10 which is a longitudinally

extending member. The tang is reduced with reference to the blade to provide a shoulder 11 or abutment transversely extending about the same for engaging with the adjacent face 12 of the guard 6 so that the face 13 of the guard is forced on the flared portion 7 and against the abutment collar 4, thus firmly holding the guard between the handle and the blade.

With the end in view of preventing the turning of the guard relatively to the handle, an interlocking connection may be provided between it and the handle held in place by the interlocking relation between the handle and the blade. In this instance, the abutment 4 has two eccentrically arranged openings 14 which receive two parallel pins 15 projecting from the face 13 to one side of the opening through the guard.

It will be seen from the foregoing that there has been provided a sword in which there is a detachable interlocking connection between the handle and the blade formed, in this instance, by a screw threaded tang on the blade received within a reduced extension on the handle, the guard being held on this reduced extension between abutments on the handle and the blade. An interlocking connection is also provided between the guard and the handle held in place by the interlocking connection between the handle and the blade. This arrangement permits the ready separation or connection of the three elements and enables the sword in a knock-down condition to be readily packed in a suitcase.

What I claim as my invention and desire to secure by Letters Patent is:

1. A sword comprising a handle having an abutment thereon, a reduced portion projecting from said abutment having an external flared portion and internally threaded, a blade having an abutment, a screw threaded tang projecting from said abutment and received in the reduced portion of the handle, and a guard held between the two abutments and having a flaring opening engaging said flared portion.

2. A sword comprising a handle having a grip portion, a blade, abutments one on each

of said parts, two interlocking parts arranged on the inner side of the grip portion between the two abutments, one on the handle and the other on the blade, one of said parts having an external wall, and a guard held between the two abutments, and having an opening fitting the external wall of the said interlocking part.

3. A sword comprising a handle having an abutment provided with an opening, a portion projecting from the abutment and provided with a flaring surface and internally threaded, a blade having an abutment, a screw threaded tang projecting from said blade abutment and engaging the internally threaded portion of the projection on the handle, and a guard fitting on the projection between the abutments tapered internally to fit the flaring surface and having a projection extending into the opening of the abutment of the handle.

4. A sword comprising a blade having a threaded tang and a shoulder at the base of the tang, a handle having a projecting portion internally threaded to receive the threaded tang, and having a shoulder at the base of the projecting portion, and a guard mounted on the said projecting portion of the handle and clamped between the shoulders of the blade and handle.
